Primary Examiner — Ricky Pham(74) *Attorney, Agent, or Firm* — Andrus, Sceales, Starke & Sawall, LLP(57) **CLAIM**

The ornamental design for a nesting chair, as shown and described.

DESCRIPTION

FIG. 1 is an isometric view of a nesting chair incorporating the new design;

FIG. 2 is a right side elevation view thereof, wherein the left side elevation view is a mirror image;

FIG. 3 is a front elevation view thereof;

FIG. 4 is a rear elevation view thereof;

FIG. 5 is a top plan view thereof;

FIG. 6 is an isometric view of another embodiment of a nesting chair incorporating the new design;

FIG. 7 is a right side elevation view thereof, wherein the left side elevation view is a mirror image;

FIG. 8 is a front elevation view thereof;

FIG. 9 is a rear elevation view thereof; and,

FIG. 10 is a top plan view thereof.

The broken lines in the drawing views are included for purposes of illustrating portions of the nesting chair that form no part of the claimed design.
